THREAD ROLLING MACHINE

Hervé Pelland, Ville Emard, Quebec, Canada

Application June 12, 1939, Serial No. 278,780

9 Claims. (Cl. 80—8)

This invention relates to improvements in thread rolling machines and in a method of rolling threads, and the primary object of the invention is to provide a machine so constructed and arranged as to roll a thread during each stroke of the machine, that is, to roll two threads during each revolution of the machine main shaft.

A further object is to provide a thread rolling machine having improved blank feeding means adapted to position blanks with accuracy and certainty and to feed the blanks so positioned to the thread rolling dies of the machine in such a way and at such time that the blanks cannot become displaced.

A still further object is to provide a thread rolling machine capable of rolling two different threads during the same period of operation.

Another object is to provide a thread rolling machine of the foregoing character capable of adjustment through a comparatively wide range to roll thread blanks of a considerable number of different sizes.

Still another object is to provide a thread rolling machine of simple, durable and compact construction which may be easily and quickly adjusted and may be operated at very low cost.

Various other objects and the advantages of the invention may be ascertained from the following description and the accompanying drawings.

As to method, the invention consists broadly in feeding blanks between relatively moving thread rolling dies, the direction of feed being in the direction of movement of a moving die at the moment the blank enters between and is gripped by the dies.

As to apparatus, the invention consists broadly in providing two pairs of relatively movable dies arranged in tandem, one die of each pair being carried by a slide operatively connected with a power driven crank shaft and the dies being so arranged that the pairs operate alternately and perform a thread rolling operation at each stroke of the slide, in combination with two blank feeding means operating alternately and in synchronism with the slide to receive blanks from magazine means and transport the blanks to the dies and feed the blanks between the dies in a direction corresponding to the direction of the adjacent moving die.

In greater detail, the invention consists, both as to method and as to apparatus, in the features and combinations of features described in the following description and/or shown in the accompanying drawings together with all such

modifications or substitutions of equivalents therefor as are within the scope of the appended claims.

Thread rolling machines at present in general use suffer from one or more of a number of structural and operative disadvantages which seriously limit the amount and perfection of the output. In the machines generally in use, a single pair of dies is provided, one being stationary and the other reciprocated past it by means of a crank shaft and connecting rod. The thread rolling operation is performed during movement of the reciprocating die in one direction but cannot be performed during the reverse or return movement of the moving die, with the result the moving die is idle while returning to its starting position. This means that half of the machine time is unproductive. Another disadvantage is that blanks are usually fed to the dies in a direction transverse of the direction of die movement with the result that the blanks are frequently improperly positioned between the dies and a defective product made.

According to the present invention, these disadvantages are overcome by providing two sets of dies alternately operating to perform a thread rolling operation during each stroke of the machine, thus doubling the production without increasing the speed of the machine and without materially increasing the power consumption.

The blank holding magazines are mounted at opposite ends of the machine and supply blanks through the usual chutes to cylindrically curved grooves extending from the chutes to the intake ends of the stationary dies. Cylindrically curved plates sliding in the grooves form chute gates and blank transferring and feeding means which move the blanks in the grip of the dies with movement in the same direction as the die movement, so that change in the direction of blank movement with consequent liability to malpositioning of the blanks in the dies is avoided.

In the accompanying drawings which illustrate one embodiment of the invention but to which embodiment and the details thereof the invention is not confined since other embodiments and modifications of detail are possible and contemplated.

Fig. 1 is a plan view of a double acting thread rolling machine showing the parts in their respective positions at full forward stroke.

Fig. 2 is a side elevation of the machine of Figure 1.

Fig. 3 is an elevation of the left hand end of the machine shown in Figures 1 and 2.

Fig. 4 is a cross-sectional view on the line 4-4 of Figs. 1 and 2.

Fig. 5 is a plan view on an enlarged scale of the die holder and feed mechanism shown at the right hand end of Figure 1.

Fig. 6 is a front elevation on an enlarged scale of the die holder and feed mechanism shown at the left hand end of Figure 1.

Fig. 7 is a rear elevation of the parts shown in Figure 6.

Fig. 8 is a bottom plan view of the parts shown in Figures 6 and 7.

Fig. 9 is a vertical longitudinal sectional view on the line 9-9 of Figure 8.

Fig. 10 is a fragmentary vertical sectional view on the line 10-10 of Figure 5.

Fig. 11 is a diagram illustrating a cycle of operation of the machine.

Referring more particularly to the drawings, 11 designated a base having a work receiving tray 12 which is preferably of the strainer type and provided with channels 13 for drawing off cutting fluid. The machine frame is rigidly mounted on the base and comprises a pair of inflexible spaced yokes 14 arranged mouth upwards and connected at the back of the machine by a heavy guide member 15 preferably L-shaped in cross-section (Figs. 3 and 4) and provided at one end with an extension 16 carrying a crank-shaft bearing 17 and counter-shaft bearing 18. At the front of the machine the yokes 14 carry tables 19 at approximately the same level as the lower arm of the guide, which tables may be separated throughout the space between the yokes, as shown in Figures 1 and 2 but may equally, if greater strength is desired, be continuous between the yokes at the front of the machine.

A crank-shaft 20 is journaled in the bearing 17 and a counter-shaft 21 is journaled in the bearing 18. The crank-shaft carries a heavy disc 22 having flywheel effect which is gear toothed at its circumference as at 23, and meshes with a pinion 24 fixed to the shaft 21. Driving means such as belt pulleys 25 is provided for the counter-shaft. The disc 22 carries a crank pin 26 on which is mounted a connecting rod 27 pivotally connected by a pin 28 to a heavy slide 27 reciprocatable on the guide 15 and retained thereon by a cap plate 30 secured to the guide.

Die holders 31 and 32 are mounted on the tables 19 and are exactly similar but are right hand and left hand as clearly shown in Fig. 1. These holders are clamped to the tables by studs and nuts or cap screws 33 passing through transverse slots 34 (Fig. 8) in the holders and into the tables. The slots 34 permit adjustment of the holders toward and away from the slide. The bottom surface of each die holder is formed with a transverse slot 35 into which fits snugly a pin or rib 36 carried by the table (Figure 6) and serving to hold the die holders against movement longitudinally of the slide.

The die holders are adjusted toward and away from the slide and are held in their adjustment by means of abutment screws 37 and traction screws 38 passing through the front arms of the yokes 14. There are two abutment screws 37 for each die holder, arranged approximately equidistantly on opposite sides of a single traction screw. The abutment screws 37 are threaded into the yokes and engage the front faces of the die holders while the traction screws merely pass through the yokes and through longitudinal slots 39 in the die holders into threaded engagement with axially vertical cylindrical nuts 40 rotatable

in the die holders and retained by cover plates 41 (Figs. 5, 6 and 8). The arrangement of slots 39 and nuts 40 enables the die holders to be angularly adjusted relatively to the slide without jamming the traction screws.

Each of the die holders is provided on its rear face with a die receiving slot 42, which is undercut at its ends in the usual manner to retain a die of usual form. The front face of the slide 10 is provided with suitably spaced die receiving slots 43 similar to the slots 42. As shown, the spacing of the slots 43 is somewhat less than the spacing of the slots 42 for reasons which will be hereafter explained. Thread rolling dies 44, 45 and 46, 47 are mounted in the slots 42 and 43 and retained by means 48, such as cap screws or studs and nuts and by wedges 49 of any suitable form. The dies 44, 46 are mounted in the holders 31, 32 and the respective cooperating dies 45, 47 are mounted in the slide.

Blank feeding mechanisms are associated with and in part mounted on the die holders 31 and 32.

The remote ends of the die holders are cylindrically curved as shown at 50, the axis of curvature being vertical and the angle subtended at the axis being somewhat more than 180°. Any suitable form of blank holding magazines (not shown) are provided at the ends of the machine and include blank chutes 51 leading to the die holders, the ends of the chutes being spaced from the curved ends of the die holders sufficiently for the passage between them of the cylindrically curved blank feeders 52 and 53, which also serve as gates controlling the escape of blanks from the magazine chutes. Associated with the curved ends of the die holders are blocks 54 each having the end adjacent the die holder concavely cylindrically curved, the radius of curvature being slightly greater than that of the die holder ends. These blocks are clamped to the tables 19 by cap screws or studs and nuts indicated at 55, with their concave ends normally parallel with and spaced from the curved ends of the die holders. The tables 19 are provided outwardly of the blocks 54 with upstanding lugs 56 carrying adjusting screws 57 threaded into the blocks to adjust the same in the longitudinal direction of the machine and toward and away from the die holders. These blocks 54 in conjunction with the curved ends of the die holders define arcuate passages 58 extending rearwardly from the lower ends of the magazine chutes and curving into the line of the gap between the dies 44, 46 and the dies 45, 47. The blank feeders 52 and 53 move freely back and forth in the passages 58 to transfer blanks from the chutes to the dies.

Each of the feeders or gates 52 and 53 consists of a cylindrically curved plate subtending at its axis of curvature an angle of slightly more than 90°. Each of the plates 52 and 53 is mounted at the outer end of an arm 59 located in a recess 60 on the lower surface of the die holder. The inner end of the arm is fixed to the lower end of a spindle 61 journaled in the die holder coaxially with the curved end surface 50 thereof. The spindle is provided with a collar 62 bearing against the upper surface of the die holder and is held in place by a cone pointed end bearing 63 engaging in the upper end of the spindle and adjustably mounted in a bracket 64 secured to the die block, as by being threaded into the bracket. If desired, a similar end bearing 65 may be provided for the lower end of the spindle, being threaded into the die holder. An actuating arm 66 is rotatably mounted at one end on

the spindle and is pressed by a spring 61 and nut 68 screwed on the spindle, against the collar 62 so as to have frictional driving engagement therewith.

The free ends of the actuating arms 66 on the two die holders are connected by a link 69 pivotally connected thereto so that the two arms and the feeders connected thereto will operate in unison. The end of this link 69 nearer the crank-shaft is connected by a universal joint 70 with a connecting rod 71 having pivotal engagement at 72 with a block 73 rotatably mounted on a crank pin 74 adjustably secured on a crank arm 75 adjustably secured to the crank pin 26 in front of the connecting rod, the arm projecting toward the centre of the disc 22, so that the crank pin 74 moves in a smaller orbit than the crank pin 26. The rod 71 is provided with length adjusting means 76.

The magazine chutes each comprise a pair of spaced parallel inclined bars 77 between which the bodies of blanks pass with their heads resting on the upper edges of the bars. The front bare of each chute is provided with a thin extension 78 bridging the passage 58 and closely overlying the die holder.

In the space between the yokes 14 and in front of the guide 15, a forwardly sloping chute plate 19 is provided. A guard plate 80 extends between the yokes above the lower end of the chute plate. A division wall 81 is mounted on the chute plate and extends from the line of the dies forwardly to the guard plate 80. The rear end of the wall is flared to right and left as shown at 82 in Figure 1, so as to deflect the threaded product forwardly. The lower edge of the wall 81, which extends at the front end below the yokes, is flared to right and left, as shown at 83, Fig. 2, so as to deflect the products of the two sets of dies in opposite directions and thus effect a separation thereof which is necessary if the products are of different sorts.

Each die holder is provided with a screw 84 passing longitudinally therethrough in the recess 60 and serving as an adjustable stop limiting the forward movement of the feeder arm 59.

It has been pointed out that the arc of curvature of the feeders or gates 52 subtends an angle of slightly more than 90°, that is to say, the feeder is somewhat more than the quadrant of a cylinder. This excess over the quadrant enables the front portion of the feeder to block the mouth of the chute when the rear edge of the feeder is at the blank delivery point, which is 90° from the chute, all as shown in Figure 5. The curvature of the die holder end beyond the semi-cylindrical is to accommodate the excess of the feeder beyond the quadrant. It will be understood the foregoing degrees of curvature are not limitative but depend upon the blank receiving and discharging points being 90° apart. If these points are either more or less than 90° apart, the circular measures of the feeders and die holder ends will be altered accordingly.

A feature of the invention is the novel form of wedges 49 used. In addition to the usual blade 85 which tapers from the back to the face of the die and from the top to the bottom of the die, there is provided a rib or flange 86 extending behind the die at an angle to the die engaging side of the blade, as clearly shown in Figures 1 and 8, and engaging in a dovetail slot in the slide or die holder. This rib positively holds a loosened wedge from leaning into the gap between the dies and being struck by and

damaging a die. In addition, the lower end of the wedge is provided with a positioning and steady pin 87 which extends below the die and steadies the lower end of the wedge where it is not tightly gripped between the die and the adjacent wall of the die slot, thus minimizing the tendency of the wedge to work loose. At the upper end of the wedge a head 88 is provided on the back of the wedge to facilitate removal.

The operation of the machine is as follows:— As shown in Figures 1 and 2, the machine is at full stroke and the slide ready to commence movement to the left. As shown in part A of the diagram Fig. 11, the right hand feeder 52 has just positioned a blank between the adjacent ends of the dies 44, 45 and the left hand feeder 53 has uncovered the end of the magazine chute and allowed a blank to move from the chute into the path of the feeder. As the crank-shaft rotates, it causes the slide 15 to move to the left so that the die 45 passes the die 44 and the blank is rolled between them and threaded in the usual manner. It will be noted the crank arm 75 is set slightly out of the centre line of the connecting rod 27, so that the feed operating crank pin 74 lags slightly behind the die operating crank pin 26 with result that the feeder 52 remains in its rearmost position long enough to ensure the blank being caught by the dies. It will also be noted the front end of the feeder 52 closes the lower end of the chute 51. After the slide 29 commences to move to the left, the feeder 52 commences to move forward and the feeder 53 to move backwards and push a blank through the arcuate slot 58 toward the die 46.

When the die 45 has passed the die 44, the rolling of a thread on the blank previously fed between them is completed, as shown in part B of Fig. 11, and the finished screw falls onto the right hand portion of the chute 79 down which it slides and escapes into a receptacle placed on the tray 12. The dies 45, 47 continue to move to the left until the die 47 completely passes the die 46, as shown in part C of Fig. 11. At this moment, the back movement of the feeder 53 is complete and a blank has been placed in readiness to be caught between the dies 46, 47 when the slide commences to move to the right. The feeder 52 has, meanwhile, uncovered the end of the magazine chute and permitted a fresh blank to pass from the magazine into feeding position in rear of the feeder (part C, Fig. 11). As the slide moves to the right, a blank is threaded between the dies 46, 47 and the feeder 52 advances a blank toward the dies 44, 45, as shown in part D of Fig. 11.

The relation of the foregoing operations to rotation of the crank-shaft is that during approximately one-third revolution a blank is threaded between dies 44, 45; the feeder 52 moves forward to receive a fresh blank and the feeder 53 moves back to place a blank in proximity to the dies 45, 47, as will be seen by comparing parts A and B of Fig. 11. During the next approximately one-sixth revolution, the die 47 moves clear of the die 46 and the blank feeding operation is completed by feeder 53 while feeder 52 uncovers the magazine chute and receives a fresh blank, as will be seen by comparing parts B and C of Fig. 11. During the next approximately one-third revolution, the blank is threaded between dies 46, 47; the feeder 53 moves forward to receive a fresh blank and the feeder 52 receives and moves a fresh blank into

proximity to the dies 44, 45, as will be seen by comparison of parts C and D of Fig. 11. During the ensuing approximately one-sixth revolution, which completes the cycle of operation, the die 45 clears the die 44 to receive a fresh blank, the feeder 52 pushes the blank in threading position and the feeder 53 uncovers the magazine chute and receives a fresh blank, as will be seen by comparison of parts D and A of Fig. 11.

From the foregoing, it will be apparent that, as regards the thread rolling operation, the only idle periods of the cycle are the two one-sixth revolutions occurring between positions B and C and between positions D and A of Figure 11. During these idle periods the dies 45, 47 move further than is necessary for thread rolling, the time of the excess movement being occupied by the blank receiving and the final part of the blank feeding operations. Because of the excess movement, or over-travel of the moving dies 45, 47, the stationary dies 44, 46 are set farther apart than the moving dies, to the extent of the over-travel, as clearly seen by comparison of the positions of die 45 in parts B and C or of die 47 in parts D and A of Fig. 11. The over-travel and the idle portion of revolution just described are now preferred, but are not absolutely necessary, since by reducing the angular travel of the feeders or increasing their speed relatively to the speed of the dies, the over-travel of the dies may be reduced.

As will be seen, the travel of the slide 15 and dies 45, 47 is not adjustable, wherefore no longitudinal adjustment of the die holders 31 and 32 and dies 44, 46 is provided for, but on the contrary, the pins 36 (Fig. 6) position the die holders precisely with reference to the slide and hold them against any slight movement that might arise from the die holders taking up clearance between themselves and their clamping screws 33 and which would detrimentally alter the relation of the feeders to the crank pin 74. The die holders are, however, adjustable toward and away from the slide to enable blanks of various diameters to be threaded. When the die holders are adjusted toward or away from the slide, the blocks 54 should be adjusted respectively inwardly or outwardly so as to obtain corresponding adjustment and substantially uniform width of the arcuate passages 58. If necessary, feeders of different thicknesses may be used according to the adjustment of the machine. The feeders themselves may be adjusted to different diameters of blanks, either by adjusting the crank pin 74 along the crank arm 75 or by adjusting the effective length of the rod 71. By adjusting the angle of the crank arm 75, the movement of the feeders may be advanced or retarded relatively to the movement of the dies, so as to exert the proper feeding pressure on the blanks at the moment they engage both dies and ensure their being grasped and rolled by the dies. If a blank should become jammed in the slot 58, the friction drive of the feeders (62, 66 of Fig. 9) will slip and protect the machine parts from damage.

During the final part of blank feeding operation, when the moving die is stationary at the moment of changing direction, the feeder places the blank between the dies. Owing to the lag of the feeder crank pin 74 behind the slide crank pin 26, the feeder is completing its movement as the moving die commences to move, so that the feeder presses the blank between the dies with pressure exerted in the direction of die movement. This final movement and pressure of the

blank in the direction of die movement is very important in ensuring that the blank is gripped and rolled by the dies.

It will be noted that in the embodiment illustrated, the upper surface of the die holders and of the blocks 54 is at substantially the same level as the upper surface of the dies. When adjusting the machine to a given diameter of blank, the die holders are adjusted toward or away from the slide and the blocks 54 are adjusted longitudinally of the slide, so that the width of the passage 58 is slightly greater than the diameter of the blank. When a blank passes from the chute into the passage 58, the blank is suspended by its head, the support being at diametrically opposite points on the blank, so that the blank tends to hang in vertical position and to be moved along the passage with its head sliding on the die holder and block 54. The upper edge of the feeder also engages under the blank head and gives an additional point of support thereto, while the advancing edge of the feeder which is vertical engages the entire length of the blank under the head and holds it in vertical position and against displacement due to vibration or other cause, so that the blank is properly presented to the dies. When the type of screw being produced does not permit of the head sliding directly on the upper surfaces of the die holders and blocks 54, any suitable auxiliary supporting means, such as is customarily used, may be provided to support the blank at a higher elevation.

Having thus described my invention, what I claim is:

1. A thread rolling machine comprising a frame; a slide therein; a pair of die holders adjustably mounted on said frame; two pairs of co-operating dies, one die of each pair being carried by the slide and the other die by one of said holders; said holders having the remote ends thereof cylindrically convexly curved about vertical axes; blocks adjustably mounted on the frame adjacent the curved ends of the die holders and having the ends thereof adjacent the die holders cylindrically concavely curved and forming with the die holders curved blank passages leading to the die; blank supplying chutes terminating at the ends of said passages remote from the dies; blank feeders oscillatable in said blank passages to transport blanks from the chutes to the dies; means to reciprocate said slide and means actuated by said slide driving means to oscillate said blank feeders.

2. Structure according to claim 1 in which the blank feeders are cylindrically curved plates of a size to serve also as gate controlling egress of blanks from the chutes.

3. A thread rolling machine comprising a frame; a slide therein; two pairs of co-operating dies, one die of each pair being carried by the frame, said die pairs being arranged in end to end spaced relation, the slide carried dies being spaced apart approximately the length of one of the frame carried dies and the frame carried dies being spaced apart a greater distance than the slide carried dies; means to feed blanks to the die pairs alternately, and means to reciprocate the slide and to actuate said blank feeding means.

4. A thread rolling machine comprising a frame; a slide reciprocatable in the frame; a die holder adjustably mounted on the frame adjacent the slide, said die holder having an end cylindrically curved about a vertical axis; a spin-

idle rotatably mounted in the die holder co-axial with the holder curvature; a blank chute terminating adjacent the curved end of said die holder; a blank feeder curved in conformity with the end of the die holder adapted to travel between the end of the blank chute and the die holder; an arm adjustably mounted on said spindle carrying said blank feeder; a collar on said spindle; a driving member rotatably mounted on said spindle; an adjustable spring means mounted on the spindle pressing said driving member into frictional driving engagement with said collar; a pair of dies mounted one in said slide and one in said die holder; and means for reciprocating said slide and for actuating said feeder driving means.

5. A thread rolling machine comprising a frame including a guide; a table beside the guide and a yoke connecting the guide and table; a slide reciprocatable in the guide; a die holder secured to the table and adjustable toward and away from the slide, said die holder having an end cylindrically curved about a vertical axis; a block secured to the table and adjustable longitudinally of the slide, said block having the end thereof adjacent the die holder concavely curved at a radius greater than the radius of curvature of the die holder, said block and die holder forming an arcuate blank passage; a blank chute terminating at one end of said blank passage; a pair of co-operating thread rolling dies mounted one on the slide and one in the die holder at the discharge end of said arcuate passage; a blank feeder oscillatable in said arcuate passage to transfer blanks singly from the chute to the dies, said feeder constituting also a gate adapted to retain blanks in the chute; and means to reciprocate said slide and to actuate said blank feeder.

6. A thread rolling machine comprising a frame; a slide reciprocatable in the frame, a pair of die holders in longitudinally spaced relation beside said slide; two pairs of co-operating thread rolling dies, the dies of each pair being mounted one in a die holder and one in said slide; blank chutes terminating adjacent remote ends of said die holders; oscillatable blank feeding means arranged to transfer blanks from the chutes to the die pairs, said feeding means each including a blank engaging blade, an actuating arm and frictional driving means operatively connecting said arm and blade; a crank shaft including a crank pin and operative connection between said crank pin and the slide; an arm adjustably mounted on said crank pin; a second

5 crank pin adjustably mounted on said arm; a linkage between the actuating arms of the two feeders; and operative connection between said second crank pin and said linkage including a universal joint.

10 7. A thread rolling machine comprising a frame; a slide reciprocatable in the frame; a pair of die holders adjacent said slide spaced in the longitudinal direction thereof; two pairs of co-operating thread rolling dies, the dies of each pair being mounted one in a die holder and one in the slide, the dies carried by said slide being closer together than the remaining dies in the longitudinal direction of the slide; a blank chute and a blank feeding means associated with each die holder; and means to reciprocate the slide and to actuate said blank feeders in synchronism with slide movement whereby a blank may be threaded during each stroke of the slide.

15 20 8. A thread rolling machine comprising a frame; a slide reciprocatable in the frame; a die holder mounted on the frame; a pair of co-operating dies one of which is mounted in the slide and the other in the die holder; a blank chute terminating adjacent the die holder; a spindle journaled in the die holder; an arm adjustably mounted on said spindle; a blank feeder mounted on said arm and constituting a gate for said chute; a collar on said spindle; an actuating arm rotatably mounted on the spindle and engaging said collar; a nut threaded on said spindle; a spring in compression between the nut and actuating arm pressing the arm into frictional driving engagement with said collar; adjustable end bearings for said spindle; a crank shaft; operative connection between the crank shaft and slide; and separate operative connection between said crank shaft and said feeder actuating arm adjustable with respect to the slide operating means, whereby the operation of the blank feeder may be advanced or retarded relatively to the operation of the slide.

25 30 40 45 9. A thread rolling machine comprising a pair of co-operating relatively reciprocating dies, a blank chute disposed in parallel with the direction of die reciprocation and adapted to deliver blanks in axially vertical position, and blank feeding means adapted to move the blanks singly in axially vertical position through an arcuate path from said chute and to feed the blanks 50 between the dies and in a direction coinciding with the direction of die movement at the commencement of the thread rolling operation.

HERVÉ PELLAND.
